UNITED STATES PATENT OFFICE.

EDWARD G. GEREKE, OF ST. LOUIS, MISSOURI.

FORM FOR SHROUDS.

1,247,663.

Specification of Letters Patent. Patented Nov. 27, 1917.

Application filed July 1, 1916. Serial No. 107,061.

To all whom it may concern:

Be it known that I, EDWARD G. GEREKE, a citizen of the United States, residing at St. Louis, Missouri, have invented a certain

5 new and useful Improvement in Forms for Shrouds, of which the following is a full, clear, and exact description, such as will enable others skilled in the art to which it appertains to make and use the same.

10 This invention relates to a device that is adapted to be used principally for imparting shape to the bust and shoulder portions of a shroud while it is being displayed for inspection or sale and for preventing the shroud from becoming creased or wrinkled while it is in transit from the manufacturer to the place where it is used or finally sold.

Prior to my invention it was the general practice among shroud manufacturers to 20 arrange tissue paper, excelsior and various other materials inside of a shroud, so as to impart shape to the shroud and prevent it from becoming creased or wrinkled, the usual practice being to first arrange the shroud in a box and then fill the bust and shoulder portions of the shroud with tissue paper or excelsior, so as to produce a form that would hold the bust portion of the shroud extended, and thus impart somewhat

25 the same appearance to the shroud that it presents when in use in a coffin. This method of preparing a shroud for display purposes and for shipment is expensive, on account of the time required for building

30 35 the bust form in the shroud and the large quantity of tissue paper, excelsior or other material that is used in said operation; it necessitates the employment of high-priced operatives possessed of considerable skill,

40 45 and it results in a product that is far from uniform, because the shape and appearance of different shrouds depends entirely upon the taste and skill of the different operatives who fill the shrouds or construct the bust forms in same. Furthermore, as the

45 50 box in which the shroud is placed is subjected to considerable jolting and rough handling while in transit from the manufacturer, the loose material used to produce the bust form invariably shifts around to such an extent that the shroud is not in a presentable condition for display purposes when it reaches the undertaker, who finally disposes of it.

55 The main object of my invention is to provide an inexpensive form for shrouds

that will impart substantially the same appearance to the bust and shoulder portions of the shroud as the shroud would present if arranged on a body; that can be installed 60 quickly and accurately, even by an unskilled operative, and which will effectively hold the shroud in shape and prevent it from becoming creased or wrinkled when the shroud is in transit from the place where it is 65 packed for shipment.

Another object is to provide a form for shrouds that can be adjusted easily to adapt it to shrouds of various bust measures, and also to enable it to be used either with a 70 shroud for a male corpse or a shroud for a female corpse.

And still another object is to provide a bust form having the characteristics above referred to which is so constructed that it 75 takes up very little space when not in use. Other objects and desirable features of my invention will be hereinafter pointed out.

Figure 1 of the drawings is a top plan view of a shroud form constructed in accordance with my invention arranged in operative position in a shroud, which is shown in broken lines.

Fig. 2 is a vertical longitudinal sectional view, taken on the line 2—2 of Fig. 1. 85

Fig. 3 is a vertical transverse sectional view, taken on the line 3—3 of Fig. 1.

Fig. 4 is an end view of my improved shroud form, adjusted to adapt it to a male shroud. 90

Fig. 5 is a top plan view of a portion of said form, illustrating one adjustment of same.

Fig. 6 is a vertical transverse sectional view of same, taken on the line 6—6 of 95 Fig. 1; and

Fig. 7 is a vertical transverse sectional view, taken on the line 7—7 of Fig. 5.

Briefly described, my improved form consists of two members, preferably formed 100 from cardboard or other suitable sheet material and provided with interlocking portions that hold one of said members, which I will refer to as the "adjustable top portion" of the form in proper position on the other member, which I will refer to as the "base plate" of the form, said co-operating interlocking portions being so formed and arranged that the adjustable top portion will have the general outline of the bust 110 and shoulder portions of a human body. The form is so constructed that the adjust-

able top portion of same can be changed easily to vary the height of the bust portion of the form and also vary the distance between the shoulder line and the bust line, 5 thus enabling the form to be used either with a high bust or low bust female shroud, or to change the general contour of said adjustable top portion, so as to adapt the form to a male shroud.

10 Referring to the drawings, which illustrate the preferred form of my invention, B designates the base plate of the form and A designates the adjustable top portion, both of which members are preferably 15 formed from sheets of cardboard or other suitable inexpensive sheet material that is more or less rigid but which can be bent without breaking. The top portion A of the form is of greatest width at its upper 20 end and is provided with two shoulder portions 1 that are arranged on opposite sides of a neck opening 2. At points intermediate the upper and lower ends of the member A slits 3 are formed in the side edge portions 25 of same, so as to permit the side edge portions of the member A to be shortened, by lapping the portions on opposite sides of the slits 3, as shown in Fig. 1, and thus cause the member A to assume a substantially 30 concavo-convex form. In other words, the member A is provided with slits 3 that extend inwardly toward each other from the side edges of said member, so as to enable the member A to be bent into a shape substantially 35 similar to the contour of the bust or chest portion of a human body, by overlapping the portions of said member lying on opposite sides of each of the slits 3. After the member A has been bent in the 40 manner described, the overlapping portions of said member are connected by means of split shank paper fasteners 4, or some other suitable retaining means. Holes 5 are preferably 45 formed in the member A at the inner ends of the slits 3, so as to eliminate sharp projections or corners on the portion of the member A that imparts shape to the breast portion of a shroud.

The base plate B acts as a support for 50 the top portion A, and said elements are provided with coöperating parts for locking them together when said elements are assembled. In the form of my invention herein illustrated the base plate B is provided adjacent its lower end with a flap 6 that projects upwardly over the lower edge portion of the top member A, and passes through a slit 7 in the member A, thus preventing the member A from moving downwardly with relation to the base plate B or upwardly off of said base plate. Adjacent the upper end of the base plate B are shoulder flaps 8 that lap over the shoulder portions 1 of the member A and project 55 into slits 9 in the member A, as shown in

Fig. 1, said shoulder flaps 8 being long enough so that they will remain in engagement with the silts 9 when the member A is adjusted to increase the height of the bust portion of the form and increase the distance between the shoulder line and bust line, as hereinafter described. The flaps 6 and 8 are preferably formed integral with the base plate B and are substantially wedge-shaped or of tapered form, so that they can be inserted easily in their coöperating slits, but I wish it to be understood that my invention is not limited to a shroud form in which the top and bottom portions of same are connected together in the manner previously described, as it is immaterial, so far as my broad idea is concerned, what means is employed for preventing relative movement of the two portions of the form and for forming the extensible shoulder portions of same. In order to provide a substantially rigid support for the upper portion of the member A, I have provided said member with a flap 10, shown more clearly in Fig. 2, that is arranged at substantially right angles to the upper portion of the member A, so that the free end of same will bear against the base plate B, said flap 10 being preferably locked to the base plate by means of a reduced extension 10^a on the end of same that passes through a slot 11 in the base plate and which is bent into a position at substantially right angles to said flap. The extension 10^a is wider than the length of the slot 11 and the end portions of said extension are scored so that they can be bent over sufficiently to permit said extension to be inserted through the slot 11, said end portions being thereafter bent back into their former positions, so as to eliminate the possibility of the extension pulling out of the slot accidentally. I also prefer to provide the flap 10 with side flanges 10^b, shown in broken lines in Fig. 1, so as to reinforce and strengthen said flap. If desired, a similar bracing element may be provided for the lower portion of the member A, such, for example, as a flap 12 arranged at substantially right angles to the base plate B and provided at its free end with a reduced extension 12^a that is adapted to be inserted through a slot 13 in the base plate in a similar manner to the extension on the flap 10 previously described. This flap 12 is 115 not essential, however, as the adjustable top portion A of the form has sufficient rigidity to hold it in shape without the aid of a supporting element at the lower end portion of the member A.

When the form is used in a female shroud the side edge portions of the member A merely rest freely on the base plate, or, in other words, are not connected to the base plate, so that the lower portion of the mem- 130

ber A will be considerably lower than the intermediate portion of said member that holds the breast portion of the shroud extended, thus causing the member A to conform 5 approximately to the outline of that portion of a female figure lying between the waist line and the breast, which, as is well known, slopes rather abruptly inwardly from the bust line to the waist line, as indicated 10 in Fig. 2. When the form is used for a male shroud, however, the side edge portions of the lower end of the member A are moved inwardly toward the longitudinal center of the form, so as to raise the lower 15 portion of the member A and impart a more abrupt curvature to same, as indicated in Fig. 4, thus causing the member A to conform approximately to the outline of the corresponding portion of a male figure. In 20 order to hold the member A in position when it is adjusted in this manner, said member is provided with flaps 14, shown in Fig. 1, that are adapted to be inserted through slots 15 in the base plate B, said 25 flaps being a trifle longer than said slots, so that the end portions 14^a of the flaps can be folded over during the operation of inserting the flaps through the slots 15, and thereafter bent back into their former position, 30 so as to prevent the flaps from pulling out of their coöperating slots. If the form is provided with an auxiliary bracing element 12, said element is disconnected from the base plate B, as shown in Fig. 4 when the 35 form is adjusted to adapt it to a male shroud, as above described.

My improved form is not only so constructed that it can be adapted to either a male shroud or female shroud, but it is also 40 so constructed that it can be adjusted easily to adapt it to female shrouds having various bust measures, the form being so constructed that the act of adjusting it to vary the height of the bust portion also changes the 45 distance between the shoulder line and bust line. As shown in Fig. 1, the member A is provided with a plurality of openings 16 for receiving the fastening devices 4, previously referred to, and the base plate B is 50 provided with a plurality of slots 11 for receiving the extension on the flap 10 that acts as a supporting element for the upper portion of the member A. If the form is to be used in a female shroud of large bust measure, the side edge portions of the member A 55 are made as short as possible, by removing the fastening devices 4 and inserting them in the lowermost holes 16 in the member A, thereby imparting greater curvature to the 60 intermediate portion of the member A and moving said portion upwardly with relation to the base plate. The act of shortening the side edge portions of the member A of course increases the distance between the 65 holes 5 in the member A and the upper end

of the base plate, which is engaged by the shoulders of the shroud, but this increase in distance is permitted by the shoulder flaps 8 which are long enough so that they will remain in engagement with the member A 70 when the form is adjusted to adapt it to the maximum bust measure.

Another characteristic of my improved shroud form which adds greatly to its commercial utility is that the neck portion of 75 same can be raised and lowered by changing the angle of the flap 10 with relation to the base plate. When the flap 10 is arranged at approximately right angles to the base plate, as shown in Fig. 2, the member A will hold 80 the neck portion of the shroud extended the maximum distance, but by disconnecting the flap 10 from the base plate and moving the free end of same upwardly so that the extension on same can be inserted in one of 85 the higher slots 11 in the base plate, the portion of the member A at the lower edge of the neck opening 2 will be brought nearer to the base plate. In other words, by arranging the extension on the flap 10 in 90 one or the other of the holes 11 in the base plate, and by varying the length of the side edge portions of the member A, the contour of the member A can be changed in various ways, so as to adapt the form to female 95 shrouds of various sizes.

The base plate B is preferably provided at its upper end with a flap 17 that acts as a closure for the neck opening 2 in the member A, said flap having wings or extensions 100 17^a which are adapted to be inserted between the shoulder flaps 8 on the base plate and the portions of the member A over which said shoulder flaps extend, so as to securely hold the neck flap in its closed position. 105 Holes 18 are preferably formed in the base plate B adjacent the upper end of same, so as to receive a string or piece of tape used to suspend the form from a supporting structure during the operation of arranging a shroud on the form, and other openings 18^b are formed in the lower portion of the base plate, said openings 18 and 18^b permitting the form with the shroud thereon to be securely attached to the bottom of the 110 box C in which the shroud is shipped, by means of pieces of string, thread or other suitable fastening devices that are passed through the bottom of the box and through the holes 18 and 18^b. 115

A form of the construction above described can be manufactured at a low cost, on account of the fact that it consists of only two members that are formed from cardboard or other suitable sheet material by 120 means of cutting dies, the various flaps on the members A and B constituting integral parts of said members and the various slots and openings in said members being cut or punched out of same by means of dies. Be- 125 130

fore the form is assembled, the two parts A and B of same are in the form of flat sheets. Consequently, the form takes up very little space when it is not in use.

- 5 To assemble the form it is only necessary to bend the flaps on the members A and B into proper position and insert them through their coöperating slots, which operation is of such a character that it can be performed 10 quickly and by an unskilled operative. The fact that the form is complete at the time the packing operation is started and is of such a character that a shroud can be arranged on same before the shroud is placed 15 in the box in which it is shipped, makes it possible to prepare a shroud for shipment in much less time than is possible by the method heretofore used in preparing shrouds for shipment. Moreover, such a form im- 20 parts substantially the same appearance to the shoud as the shroud presents when ar- ranged on a body, and it effectively holds the shroud in position and prevents it from becoming creased or wrinkled while it is in 25 transit, owing to the fact that the form as an entirety can be stitched or secured in any other manner to the bottom of the box in which the shroud is shipped. The form can be adjusted easily to adapt it to male 30 shrouds or female shrouds or to raise or lower the bust portion of the shroud and the adjacent neck portion; and still another desirable characteristic of such a form is that it comprises a portion that forms a 35 support for the collar of the shroud or for any material that is arranged in the neck opening of the shroud, so as to impart a finished appearance to the shroud.

While my improved form is intended to 40 be used principally for shrouds, I wish it to be understood that it is not limited to this specific use, as it can be used in connection with various other kinds of men's or women's garments for imparting shape to 45 same and for preventing creasing or wrinkling of the breast and shoulder portions of same.

Having thus described my invention, what I claim, and desire to secure by Letters Patent, is:

1. A form for the purpose described, comprising a base plate, an adjustable top portion of substantially curved form in cross section arranged above said base plate and 55 provided with means whereby it can be adjusted to vary the cross-sectional shape of said top portion and raise and lower it relatively to said base plate, and shoulder flaps on one of said elements arranged in sliding 60 engagement with the other element.
2. A form for the purpose described provided with a base plate, a top part having shoulder portions that slope upwardly from said base plate and merge into a breast portion, integral shoulder flaps on said base 65
- plate that lap over said top part and project through slots in same, means for enabling said top part to be adjusted so as to change the elevation of said breast portion, and independent means for enabling the lower 70 portion of said top part to be raised and lowered with relation to the base plate.
3. A form for the purpose described provided with a base plate, a top part having shoulder portions that slope upwardly from 75 said base plate and merge into a breast portion, shoulder flaps on said base plate that lap over said top part and project through slots in same, means for enabling said top part to be adjusted so as to change the ele- 80 vation of said breast portion, independent means for enabling the lower portion of said top part to be raised and lowered with re- 85 lation to the base plate, and a neck flap on said base plate that laps over said top part at points intermediate said shoulder flaps.
4. A form for the purpose described, consisting of a bottom member and a top mem- 90 ber formed from sheet material and ar- ranged in superimposed relation, said top member being provided with means that en- ables the side edge portions of said member to be lengthened and shortened so as to im- part a substantially curved form to said top member both longitudinally and trans- 95 versely, means for securing the lower edge portions of said members together, and integral shoulder flaps on said bottom member that lap over said top member and project through slots in same. 100
5. A form for the purpose described, con- 105 sisting of a bottom member and a top mem- ber formed from sheet material and ar- ranged in superimposed relation, said top member being provided with means that en- ables the side edge portions of said member to be lengthened and shortened so as to im- 110 part a substantially curved form to said top member both longitudinally and trans- versely, means for securing the lower edge portions of said members together, shoulder flaps on said bottom member that lap over 115 said top member and project through slots in same, an adjustable supporting element arranged between said members adjacent the upper ends of same for enabling one portion of said top member to be raised and lowered with relation to said bottom mem- 120 ber, and an independent means for enabling the cross-sectional curvature of the lower portion of said top member to be varied.
6. A form for the purpose described, con- 125 sisting of a bottom member and a top mem- ber formed from sheet material and ar- ranged in superimposed relation, said top member being provided with means that en- ables the side edge portions of said mem- 130 ber to be lengthened and shortened so as to im- part a substantially curved form to said top member both longitudinally and trans-

versely, means for securing the lower edge portions of said members together, shoulder flaps on said bottom member that lap over said top member and project through slots in same, an adjustable supporting element arranged between said members adjacent the upper ends of same for enabling one portion of said top member to be raised and lowered with relation to said bottom member, an independent means for enabling the cross-sectional curvature of the lower portion of said top member to be varied, a neck opening in said top member, and a neck flap on said bottom member that closes said neck opening.

EDWARD G. GEREKE.
